UNITED STATES PATENT OFFICE.

JOHN B. COOK, OF LANSING, MICHIGAN.

TROUSERS-STRETCHER.

SPECIFICATION forming part of Letters Patent No. 529,600, dated November 20, 1894.

Application filed February 10, 1894. Serial No. 499,736. (No model.)

To all whom it may concern:

Be it known that I, JOHN B. COOK, a citizen of the United States, residing at Lansing, in the county of Ingham and State of Michigan, have invented certain new and useful Improvements in Trouzers-Stretchers, of which the following is a specification, reference being had therein to the accompanying drawings.

10 This invention relates to a new and useful improvement in trousers stretchers and consists in the construction and arrangement of parts hereinafter described and definitely pointed out in the claims.

15 In the drawings, Figure 1 is a perspective view of my improved device, showing the trousers thereon, the frame being adjusted to stretch the same. Fig. 2 is a rear elevation.

20 Fig. 3 is a vertical, central section on line x x. Fig. 4 is a section on line y y, Fig. 1. Fig. 5 is a section on line z z Fig. 2. Fig. 6 is a perspective view of the bars separated showing the joints for uniting the bars and the detachable creasing ribs. Fig. 7 is a cross section 25 thereof. Fig. 8 is a longitudinal section therethrough, illustrating the construction of this joint.

Each stretcher frame comprises two leg stretchers, and each leg stretcher comprises the front bar A, and the rear bar B. These bars are provided on the contiguous faces on their lower ends with the screw threaded pins a, and near the upper ends with the pins b, the ends of these pins being connected together by means of the turnbuckle c. The rear bar B is straight in its lower section, but near the upper end it is provided with the seat bend C. The pins b and turnbuckle c should be located near enough to the top of 40 these bars so that it may be conveniently reached through the top of the trousers after they are on the frame and yet it should be below the bend C of the rear bar, so that in adjusting the upper turnbuckle c the stretcher

45 bars will turn about the lower pin a and thus give a greater outward movement to the upper ends of said bars. These bars may be made of wood or metal and may have rounded edges or pointed edges as desired, the pointed edges being used where it is desired to form a crease in the trousers.

In Fig. 4 I have shown the bars as formed

of wood and having the creasing edges d formed by simply shaping the bars.

In Figs. 6, 7 and 8 I have shown a construction employing tubular bars e having detachably secured on one face the creasing rib f, which I have shown as formed of sheet metal, bent into substantially trough shape and detachably secured in position by means of the screws g.

I preferably make the bars in sections for convenience in packing and shipping. This I have illustrated in Figs. 6 and 8, in connection with the tubular bars, and in this construction I form in the end of one of the sections pins h adapted to fit tightly in the end of the adjoining section. In this construction the creasing rib is made correspondingly in sections and the joint between the sections 70 is spanned by means of the interlocking or overlapping strip i, secured on the inner end of one section and adapted to project beneath the adjoining section. Each leg stretcher thus formed of two bars adjustably secured together by a connection on their contiguous faces forms but a half of the frame. The two leg stretchers are adjustably connected together near their upper portions by the pins G on the inner faces of the front and rear 80 bars respectively and the turnbuckle I connecting the ends of the pin. E are pins extending from the inner faces of the rear bars above the adjustable connections between the two leg stretchers. The ends of the pins are 85 connected together by the turnbuckle F. It will be seen that the connections E F act as a brace and prevent the lower ends of the leg stretching portions from spreading or coming together and enables the two leg stretching 90 portions to be adjusted relative to each other when the turnbuckles I are adjusted and fixedly held in their adjusted position.

The parts being thus constructed, their operation is as follows: The turnbuckles are rotated to reduce the size of the leg stretchers and to cause them to approach together sufficiently near, so that the trousers to be stretched can be easily engaged therewith. The trousers may then be supported by buttoning them to the tabs H at the upper end of the bars. Now by adjusting the turnbuckle c, each leg will be tightly stretched about the leg stretcher and the body may be tightly

stretched by turning the turnbuckle F to the proper amount. This not only eradicates the bagging of the knees and wrinkles but also forms a frame upon which the trousers may be tightly stretched for cleaning or brushing.

5 What I claim as my invention is—

1. In a trousers stretcher, the combination of two leg stretchers, each comprising a front and rear bar, the rear bar having the straight 10 lower portion and the curved upper portion forming the seat bend, a turn-buckle connecting the lower portions of the respective front and rear bars, a turn-buckle connecting the respective front and rear bars at or near the 15 curved seat portion of the rear bar, adjustable connections G—I between the pair of leg stretchers, and the brace E—F between the

pair of leg stretchers and above the connections G—I, substantially as described.

2. In a trousers stretcher, the combination 20 of two leg stretchers, each comprising a front and rear bar and consisting of two sections detachably connected together, independent creasing ribs detachably secured to the bars, consisting of two sections, and the overlapping 25 strip *i* secured on the inner end of one section and adapted to project beneath the adjoining section, substantially as described.

In testimony whereof I affix my signature in presence of two witnesses.

JOHN B. COOK.
